UNITED STATES PATENT OFFICE.

EWALD HANUS, OF TEGEL, NEAR BERLIN, GERMANY, ASSIGNOR TO DEUTSCHE WAFFEN- & MUNITIONSFABRIKEN, OF BERLIN, GERMANY

BALL-GRINDING MACHINE.

1,051,885.

Specification of Letters Patent.

Patented Feb. 4, 1913.

Application filed July 5, 1912. Serial No. 707,915.

To all whom it may concern:

Be it known that I, EWALD HANUS, engineer, a subject of the King of Prussia, residing at No. 14 Treskowstrasse, Tegel, 5 near Berlin, Germany, have invented certain new and useful improvements in Ball-Grinding Machines, of which the following is a specification.

This invention relates to a ball grinding 10 machine with annular grooved disks, wherein the balls are passed by a gap in one grinding disk out of the grooves, mixed and thereupon led to the grooves again.

The invention has for its object to lead 15 the balls out of the grinding grooves, to mix the balls and to lead them again into other grooves while avoiding the disadvantage of the known arrangements in that the balls are compelled to pass through closed 20 channels or over long rolling planes or surfaces protruding laterally from the grinding disks.

Consequently, the invention consists in 25 passing the balls out of the grinding grooves on to two juxtaposed undivided guiding members, which crossing over each other in the form of a curve are directed toward the middle of the gap in the grinding disk and terminate over a lower undivided guiding 30 member, on which they guide the balls in two oppositely directed streams and on which the balls roll again to the grinding grooves. The effect to be attained thereby 35 is that the energy with which the balls leave the grinding grooves, is retained by the balls as far as possible in that the path up to their reentrance is only a short one corresponding to the extent of the gap in the grinding disk and the balls on this path 40 have no resistances to overcome when passing through inlet and outlet channels but roll freely on the guiding members and fall through the mixing chamber, so that when the balls reenter the grinding grooves, 45 they possess approximately that speed, which corresponds to the speed of the grinding disks. Consequently, special means for attaining an additional speed of the outgoing balls before reentering the grinding 50 grooves are superfluous. The same advantage as with the machines working with artificial additional speed is however attained in that the speed of the grinding disks is considerably increased and the

duration of the actual grinding process for 55 a charge of balls is correspondingly decreased and the quality of the balls is improved. The useful effect of these machines is consequently much more satisfactory. It is moreover increased by the aforesaid omission of the positive channel system, which 60 is subjected to a rapid wear and tear and therefore requires a frequent expensive renewal, and also by the possibility of using the grinding machine without any alteration 65 for balls of different diameters within certain limits, as, for instance, for the sizes of $\frac{1}{2}$ to $\frac{1}{4}$ inch, which in connection with machines with positive guiding of the balls is not admissible for the purpose of mixing, 70 because in these machines, the admission and discharge channels must correspond exactly with the diameters of the balls.

The invention is shown in the drawing as applied to a ball grinding machine with 75 vertically disposed disks.

Figure 1 is a horizontal section through the grinding disks at the gap and Fig. 2 is a vertical section according to 2—2 of Fig. 1.

The balls issuing uniformly from all grooves 80 at the gap fall freely upon the two curve-shaped grinding members *a* and *b*, which are relatively bent and cross over each other. The said guiding members extend approximately half-way of the width of the gap. 85 They guide the balls in two oppositely directed streams on to the guiding member *c* underneath, on which the balls roll again to the grinding grooves and in such a manner that the balls coming from the outer 90 grooves preferably pass into the inner grooves and those coming from the inner grooves pass into the outer grinding grooves. The incoming and outgoing of the balls take place without loss of energy, so that a decrease 95 of their speed and a jamming at the inlet is prevented and the working of the machine can remain continuous even when filling same with the largest possible number of balls. After a large number of grinding-charges with balls of the same size, as, for example, $\frac{1}{2}$ ", is carried out and a wear and tear of the grinding grooves has taken place to such an extent that the size of the 100 grooves has become suitable for balls of $\frac{5}{8}$ ", the machine constructed according to the present invention can be used without any alteration for $\frac{5}{8}$ " balls then for $\frac{3}{8}$ ",

$\frac{3}{2}$ " and so forth to $\frac{1}{4}$ ", because the means used for feeding and leading away the balls are independent of the size of the balls.

I claim:

- 5 1. In a ball grinding machine, the combination of two coöperating grinding disks disposed in a vertical plane, one of which is stationary and the other movable, said grinding disks being formed with a plurality of annular grooves in their working faces and said stationary disk having a space to permit the discharge of the balls from said grooves, two juxtaposed curved guiding members located in the upper part 10 of the space crossing each other and directed toward the median portion of the space to receive the balls passing out of the grooves, and an undivided guiding member located in the lower part of the space and 15 adapted to receive the balls discharged from the said upper grinding members and to return said balls into said grooves.
2. In a ball grinding machine, the combination of coöperating grinders formed with a plurality of grooves in their working faces, a plurality of converging guiding members extending in a downward direction 20 from said upper grinding members and to return said balls into said grooves.
- 25 3. In a ball grinding machine, the combination of two vertically disposed coöperating grinders formed with a plurality of ball grooves in their working faces, a plurality of juxtaposed curved and substantially short guiding plate members converging in a downward direction from said grooves toward the median portion of a space formed in one of said grinders, and an additional downwardly extending and substantially short guiding plate member which is arranged substantially inversely to 30 said other guiding members and adapted to receive the balls therefrom and to re-con- duct said balls into said grooves.

In testimony whereof I have affixed my signature in presence of two witnesses.

EWALD HANUS.
